LEOPOLDO SANCHEZ VELLO, OF PARIS, FRANCE

BULB, TUBE, OR OTHER HERMETICALLY CLOSED RECEPTACLE FOR INCANDESCENT ELECTRIC LAMPS AND SIMILAR DEVICES AND PROCESS OF MANUFACTURE OF THE SAME

Application filed October 21, 1922, Serial No. 596,172, and in Spain October 29, 1921.

This invention relates to hermetically closed devices, such as electric incandescent lamps, X-ray tubes, three electrode tubes and like electric bulb apparatus, of that type which may be 'reclaimed' or 'regenerated', by which is meant devices which may be opened up by means of a readily fusible joint so that the filament may be renewed after burning out or breakage thus obviating the throwing to waste of the remaining valuable undamaged parts of the device. The object of the invention is to provide an improved, simple and less expensive device of the aforesaid type in which it has been the custom in the past to form the bulb by the usual blow-pipe method and then secure the same with cement or some other adhesive to a metal base by which the device could be secured in its electrically connected socket.

Fig. 1 is a view of a lamp bulb partly in section with the bulb, cover, and joint ring separated.

Fig. 2 shows a finished lamp.

Fig. 2a is a similar view partly in section.

Fig. 3 is a plan view of Fig. 1.

Fig. 4 is an enlarged sectional view showing the globe and cover assembled.

Figs. 5—6—7 and 8 are detail views of the electric contacts in section and plan.

As shown in Fig. 1 herewith, the lamp consists of a bulb 1 made of glass and cut across and smoothed by grinding on the line X—X. The reference numeral 2 indicates a ring of glass or the like, the inside diameter of which approximates that of the mount of the bulb, the fusing point of this ring being much lower than that of the parts 1 and 3, although its coefficient of expansion is about the same.

The cover 3 constitutes the base of the lamp in which the wires 14 and 18 entering the lamp are fused, and itself forms a socket connection for the lamp. The rod 4 as shown is intended for use when a metal filament is employed, and may be dispensed with when the filament is of carbon.

If the said cover is to serve as a screw base, it is provided with two metal contacts 12 and 13 embedded in the glass and formed respectively as shown in Figs. 6 and 8. The con-

tact 13 makes the electric connection between the wire 14 and the screw threaded base, the said wire being imbedded at the centre of the cover and the contact 13 being disposed in the groove 49a formed in the cover, with the curved end 16 in the thread of the screw of the cover.

In this way, when the end of the wire 14 is soldered at 17 to contact 13, the current enters by way of 16—13—17—14.

As stated above the wires 14 and 18 are embedded in the glass and pass through the central portion 19 of the cover 3. This cover is preferably made of moulded glass and in a co-pending patent application Serial No. 596,173 patent No. 1,606,276, dated November 9, 1926 the process and apparatus for the production of this device are shown and described.

When the three parts, 1—2 and 3 of the lamp are manufactured, and the filaments are positioned the lamp may be completed by melting the ring 2 thereby connecting the said three parts and then producing a vacuum in the bulb.

It is not absolutely necessary to make this said ring 2 separate from the bulb and cover, as it could be formed upon the edge of either and a joint made by applying a rod of more readily fusible glass around the said edges.

It is obvious that with a lamp of this construction, if the filaments should become inoperative it is only necessary to melt the ring 2 thereby separating the bulb 1 from the cover 3. The interior parts could then be repaired or renewed and the lamp assembled as before.

I do not desire to limit myself strictly to the precise form shown and described herein as there are a number of modified forms within the scope of my invention as disclosed herewith.

I claim:—

1. A process for making an electric hermetically closed vessel, comprising the steps of blowing a glass bulb having one end open, moulding a solid head having socket engaging means and filament supporting means of a single mass of vitreous material, and with leading-in wires and contacts encrusted in

- the mass, mounting a filament on the filament supporting means of the head, and in electrical connection with said leading-in wires and contacts, and uniting the blown bulb and moulded head by means of a vitreous joint of greater fusibility than either of said parts, and in such manner that said head closes the open end of the bulb, the air content of the device being treated as required.
- 15 2. A process of forming a hermetically closed vessel of the class described, consisting in blowing a glass bulb with an open end, moulding under pressure a solid glass head with integral socket-engaging projections and filament supporting means, and simultaneously embedding therein the electric current connections of the filament system of the device and mounting a filament thereon, uniting the open end of the blown bulb to the corresponding part of the moulded head by a ring of glass with a lower fusing point than the glass of either the bulb or head, the whole being welded together by subjecting the assembled parts to a temperature that will fuse 25 the ring without fusing the parts to be connected and evacuating the bulb.
3. An evacuated electric hermetically closed vessel comprising a glass bulb having an open end, a solid glass head having a coefficient of expansion different from that of the said bulb, and comprising integral socket-engaging projections and a filament supporting means, electric current connections embedded in said head, a filament mounted upon 35 the filament supporting means, and a separate ring of glass of greater fusibility than that of the head and bulb which unites these two parts so as to close the vessel.
4. A hermetically closed vessel comprising 40 a unitary head of massive vitreous material and forming the sole direct means of attachment of the device to a supporting socket and also having a filament supporting stem integral therewith, a filament system with contacts and leading-in wires embedded in said head, an open ended glass bulb having a coefficient of expansion different from that of the said head, and a separate fusible glass ring which unites the head and bulb to complete the closure of the device.
5. A hermetically closed vessel, comprising 45 a unitary head of massive vitreous material with external screw threads whereby the head forms the sole means of attachment of the device to a supporting socket and also having a filament supporting stem integral therewith, a filament system with contacts and leading-in wires embedded in said head, an open-ended glass bulb having a coefficient of 55 expansion different from that of said head, and a separate fusible glass ring which unites the head and bulb to complete the closure of the device.
6. A hermetically closed vessel comprising 60 a unitary head of massive vitreous material, an integral rim formed upon said head, external means upon said head whereby the latter forms the direct means of attachment of the device to a supporting socket, a filament supporting stem integral with said head, a filament, and leading-in wires having their entire length except the portions inside the bulb embedded hermetically in the mass of the head, contacts joined to the leading-in wires also embedded in the head, a glass bulb having a coefficient of expansion different from that of the said head, and a separate easily fusible glass ring which unites the bulb and the rim of the head to complete 70 closure thereof.
- In witness whereof I have hereunto signed my name.
